UNITED STATES PATENT OFFICE.

ALBERT H. CENTNER, OF CHICAGO, ILLINOIS.

ELEVATING ROLLER ATTACHMENT.

SPECIFICATION forming part of Letters Patent No. 705,905, dated July 29, 1902.

Application filed March 14, 1902. Serial No. 98,212. (No model.)

To all whom it may concern:

Be it known that I, ALBERT H. CENTNER, a citizen of the United States, residing at Chicago, in the county of Cook and State of Illinois, have invented new and useful Improvements in Elevating Roller Attachments, of which the following is a specification.

This invention relates to an elevating roller attachment of that class designed to conveniently transport heavy articles, such as domestic machines, heavy household furniture, and store and office furniture or other heavy articles to which ordinary rollers cannot be practically or conveniently applied.

15 The main object of the present improvement is to provide a simple and effective device capable of being disposed in stable position to receive the article, machine, or other device to be moved or transported thereby and afterward adjustable to bring the rollers into engagement with the surface on which the attachment is resting and disengage the legs of the attachment from such surface.

25 A further object in view is to provide an elevating roller attachment having simple and readily-operated means for suspending the rollers thereof in operative relation in such a manner as to resist any tendency toward inoperative disposal of the rollers by 30 the weight imposed upon the attachment.

With these and other objects and advantages in view the invention consists in the construction and arrangement of the several parts, which will be more fully described and 35 claimed hereinafter.

In the drawings, Figure 1 is a perspective view of the improved roller attachment, showing it arranged to bring the rollers in contact with the surface over which the device is to 40 move in full lines and the roller elevated out of operative position in relation to the supporting-surface in dotted lines. Fig. 2 is a top plan view of the improved attachment. Fig. 3 is a transverse vertical section of the 45 same.

Similar numerals of reference are employed to indicate corresponding parts in the several views.

The numeral 1 designates a series of uprights, four of the latter being used in the present instance and inwardly converged toward their upper ends, where they are con-

nected to a supporting-bed. The legs are attached to a horizontally-disposed spider 3, which may be of any suitable form and provided with a central web 4, with an aperture therethrough. The uprights at a distance slightly below the spider 3 flare or project outwardly to increase the area of the base-rest of the uprights, so as to give the improved device a more stable position in relation to the surface on which it is disposed. Two of the uprights 1 are connected near their lower ends by a bar 5, for a purpose which will be hereinafter set forth; and to the inner edges 6 of the said uprights near their lower ends levers 6 are hinged or movably attached and have outer depending extremities 7 to form feet, which are provided with antifrictional ball-rollers 8, adapted to have movement in any direction without obstruction. The levers 6 are continued inwardly in substantially horizontal radial planes and have their inner ends bifurcated, as at 9, to loosely receive oppositely-disposed tongues 10, carried by a central adjusting-table 11, the tongues 10 being formed with longitudinal slots 12 to receive the connecting-bolts 13, passed through the inner bifurcated ends of the levers 6 and the said tongues to compensate for the movement 80 of the levers 6 at an angle when the balls 8 of the feet 7 are thrown out of engagement with the surface on which the attachment is disposed and as clearly shown by dotted lines in Fig. 1.

Rising from the center of the table 11 and rigidly attached to the latter is an upright spindle 14, freely movable through the web 4 of the spider 3 and serving to cause the several levers to be uniformly adjusted, either 90 to throw them out of contact with the surface over which the device is disposed or to bring the balls or rollers 8 into operative engagement with said surface.

Secured to the center of the bar 5 is one 95 end of a treadle 15, the opposite end of the latter being attached, by a flexible connection 16, to a loop 17, depending from the under side of the table 11. Loosely depending from the spider 3 is a locking rod or bar 18, which is adapted to have its lower end brought in contact with the treadle 15 to hold the table 11 in its lowered position and maintaining the rollers 8 in engagement with the surface on

which the device is disposed, and thus resist any tendency of the said rollers to become disengaged from the surface over which the attachment is moved or thrown up, as shown 5 in dotted lines by Fig. 1, by the weight of the device supported on the bed 2.

In the use and operation of the device one or more of the same is placed under the article or structure to be transported or moved 10 from one place to another, and during the disposal of the device to be moved on the bed 2 the lower ends of the uprights are brought into contact with the surface over which the attachment is to be shifted. After the device 15 to be transported is disposed on the bed 2 pressure is exerted on the treadle 15 by the foot of the operator, and the table 11 is brought down to the position shown in full lines, so as to elevate the bed 2 or throw the feet 7 of 20 the levers 6 into such position that the rollers or balls 8 will depend below the lower ends of the uprights 1 and replace the said lower ends of the uprights to support the attachment and the weight imposed thereon. After the 25 levers 6 are brought down into the position shown by Fig. 1 they are locked against accidental displacement from such position by moving the rod 18 until the lower end thereof contacts with the upper surface of the 30 treadle, and thereby the rollers or balls 8 will be held in practically projected position. The article of furniture or other device held on the bed 2 will then be free to be rolled or readily moved over the surface on which the 35 balls or rollers 8 have bearing. When the article of furniture or device transported by the improved attachment is moved to the position or place desired, the rod 18 will be released and the lower ends of the uprights 1 40 will be again uniformly brought into contact with the surface previously engaged by the balls or rollers 8.

From the foregoing it will be seen that an exceptionally simple, strong, and durable attachment is provided for moving heavy articles, and the expense of manufacture of the same is reduced to a minimum in view of the simplicity of the structure. It is proposed to form the improved attachment of any kind 45 of metal and to reinforce the parts whenever found necessary.

The parts of the improved device may be suitably ornamented, painted, or otherwise coated, and to suit various uses changes in 50 the proportions, dimensions, and form may be resorted to without in the least departing from the principle of the invention.

Having thus described the invention, what is claimed as new is—

60 1. An elevating roller attachment of the class set forth comprising a series of uprights connected to an upper bed, a series of levers

movably connected to the inner portions of the uprights and having depending feet with rollers thereon, a central, movable device to 65 which the said levers are attached, and a treadle connected to said movable device for throwing the rollers of the levers into operative position.

2. An elevating roller attachment comprising 70 upright devices having levers movably connected thereto, the said levers being provided with depending feet having rollers thereon, and centrally-located means for operating the levers and throwing the rollers 75 thereof below the lower ends of the said devices.

3. An elevating roller attachment of the class set forth comprising a series of upright supporting devices, levers movably attached 80 to the inner portions of said devices and provided with outer depending feet having rollers thereon, central operating mechanism connected to said levers for throwing the rollers of the latter below the lower ends of 85 the upright supporting devices, and means for locking the said central operating mechanism against movement when the rollers on the levers are depressed.

4. An elevating roller attachment of the 90 class set forth, comprising a series of uprights, levers attached to the inner, lower portions thereof and provided with outer depending feet having rollers thereon, a spider horizontally disposed and connected to the uprights 95 above the plane of the levers, a central table attached at opposite points to the levers and provided with an upwardly-projecting spindle movable through the spider, and a treadle attached to the table for lowering the latter and 100 throwing the rollers on the levers into operative position.

5. An elevating roller attachment of the class set forth, comprising a series of uprights, levers attached to the inner, lower portions 105 thereof and provided with outer depending feet having rollers thereon, a spider horizontally disposed and connected to the uprights above the plane of the levers, a central table attached at opposite points to the levers and 110 provided with an upwardly-projecting spindle movable through the spider, a treadle attached to the table for lowering the latter and throwing the rollers on the levers into operative position, and a locking-rod loosely depending from the spider and adapted to engage the treadle. 115

In testimony whereof I affix my signature in presence of two witnesses.

ALBERT H. CENTNER.
